NOVEL CARBOXYMETHYLAMINO BENZENES
USED IN HAIR DYES

Gregoire Kalopissis, Paris, and Andrée Bugaut, Boulogne-sur-Seine, France, assignors to L'Oréal, Paris, France
 No Drawing. Filed Apr. 21, 1966, Ser. No. 544,079

ABSTRACT OF THE DISCLOSURE

Hair dye compounds selected from the group having the formulas:

(I)

(II)

(III)

in which n is 1 to 4.

Nitroparaphenylenediamine is a well known ingredient in hair dyeing solutions. This dye, when cold, has an excellent affinity for keratinic fibers, but is incapable of producing any colors other than red-orange shades.

On the other hand, in order to produce deeper shades, that is to say, shades tending toward green, the use of substituted derivatives of nitroparaphenylenediamine has been suggested. In particular, it has been found that the introduction of a CH_3 radical on the amine function in the meta position with respect to the NO_2 radical of nitroparaphenylenediamine deepens the shade. However, the products obtained in this manner can be used only within a relatively restricted range of pH values on either side of the neutral point.

The purpose of the present invention is to alleviate this difficulty by providing new dyes which produce even deeper shades, that is to say, tending more toward the blue, which may be used over a wider range of acid pH values. The object of the invention is therefore to provide a new article of manufacture which consists of a dye for keratinic fibers and especially for hair, which dye is essentially char-

2

acterized by the fact that it contains at least one derivative of nitroparaphenylenediamine having the formula:

in which R' may represent hydrogen, or a methyl radical and R may represent either CH_3 or the radical

15 and n is a whole number falling between 1 and 4 inclusive.

The dyes defined in this manner make it possible to obtain deep shades in the blue portion of the spectrum over a wide range of acid pH values and especially between pH 20 3 and pH 10.

Another object of the present invention is to provide the new article of manufacture which consists of the new chemical compound derived from nitroparaphenylenediamine, and responding to the above formula.

25 A further object of the present invention is to provide a new method of dyeing keratinic fibers, and especially human hair, which method is essentially characterized by the fact that an aqueous solution comprising at least one dye responding to the above formula is applied to the hair, 30 and that after from about 15 to 40 minutes of application the hair is rinsed, shampooed, and dried.

In order that the invention may be better understood, several embodiments thereof will now be described, purely by way of example.

EXAMPLE 1
Preparation of monohydrochloride of 1-methylamino-2-nitro-4-carboxymethylamino benzene

40 The method of preparing the above compound is new. It is essentially characterized by the fact that 1-methylamino-2-nitro-4-amino benzene is reacted with chloroacetamide to obtain 1-methylamino-2-nitro-4-carbamylmethylamino benzene, and that the amide function of the 45 resulting compound is hydrolyzed with hydrochloric acid to yield the monohydrochloride of 1-methylamino-2-nitro-4-carboxymethylamino benzene. This process may be represented by the following diagram:

65 (a) Preparation of 1-methylamino-2-nitro-4-carbamylmethylamino benzene.—A mixture of 0.2 mols (33.4 g.) of 1-methylamino-2-nitro-4-amino benzene, 450 cm.³ of water and 10 g. of calcium carbonate is boiled to reflux. While stirring, 0.214 mols (20 g.) of chloroacetamide is introduced. Reflux is then continued for an hour. After cooling, drying yields 40 g. of 1-methylamino-2-nitro-4-carbamylmethylamino benzene, which, after recrystallization in acetic acid and dioxane, melts at 167° C.

Analysis.—Calcd. for $C_9H_{12}O_3N_4$ (percent): C, 48.21; H, 5.35; N, 25.00. Found (percent): C, 48.14–47.99; H, 5.35–5.30; N, 25.19–25.00.

(b) Preparation of monohydrochloride of 1-methylamino-2-nitro-4-carboxymethylamino benzene.—0.085 mols (19 g.) of 1-methylamino, 2-nitro-4-carbamylmethylamino benzene is introduced into 150 cm.³ of concentrated hydrochloric acid, while stirring it and boiling it to reflux. Reflux is continued for 30 minutes. The mixture is cooled and on drying, yields 16 g. of monohydrochloride of 1-methylamino - 2 - nitro - 4 - carboxymethylamino benzene, which, after recrystallization in concentrated hydrochloric acid, melts at between 163° C. and 166° C.

Analysis.—Calcd. for $C_9H_{12}O_4N_3Cl$ (percent): C, 41.30; H, 4.58; N, 16.06. Found (percent): C, 41.48–41.51; H, 4.90–4.88; N, 16.12–16.10.

EXAMPLE 2

Preparation of 1 - methylamino-2-nitro-4-(N,N-methyl carboxymethyl) amino benzene

The above compound is prepared by a new method essentially characterized by the fact that the primary amine function of 1 - amino-2-nitro-4-N,N-methyl-carbamylamino benzene is blocked, using para-toluene sulfochloride, for example, after which a methyl radical is substituted for the free hydrogen remaining on this primary amine function, using for example methyl sulfate in a basic medium. The tosyl radical fixed in the first step of the process is then eliminated, using concentrated sulfuric acid, for example. The amide function of the resulting compound is then hydrolyzed with concentrated hydrochloric acid, for example, and the monohydrochloride of 1 - methylamino, 2 - nitro (N,N,methylcarboxymethyl)-4-amino benzene results. The process which has just been described is schematically represented by the following diagram:

(a) Preparation of para-toluene-1-sulfonylamino-2-nitro - 4-(N,N,methylcarbamylmethyl)amino benzene.—0.953 mols (181 g.) of para-toluene-sulfochloride is added little by little, while stirring to 0.866 mols (194 g.) of 1-amino-2-nitro-4-carbamylmethylamino benzene at 45° C. The mixture is kept at 40° C. for 4 hours and then poured into 4 liters of ice water to which 525 cm.³ of concentrated hydrochloric acid has been added. When dried, a crude product is yielded which is then redissolved in an 0.5 N solution of sodium hydroxide. The solution is then filtered to eliminate any of the initial product which remains uncombined. After the filtrate has been acidified with hydrochloric acid it yields on drying 229 g. of para-toluene - 1 - sulfonylamino-2-nitro-4-(N,N-methylcarbamylmethyl)amino benzene which after recrystallization in alcohol, melts at 181° C.

Analysis.—Calcd. for $C_{16}H_{18}N_4O_5S$ (percent): C, 50.79; H, 4.76; N, 14.81. Found (percent): C, 50.89–50.88; H, 4.83–4.86; N, 14.97–14.86.

(b) Preparation of N' - methyl-N'-para-toluene sulfonylamino - 2 - nitro (N,N,methyl-4-carbamylmethyl) amino benzene.—0.945 mols (90 cm.³) of methyl sulfate is added little by little, at between 35° and 40° C. to a solution of 0.424 mols (160 g.) of para-toluene-1-sulfonylamino - 2 - nitro-4-(N,N,methyl-carbamylmethyl) amino benzene in 1250 cm.³ of 0.5 N sodium hydroxide, while simultaneously adding 800 cm.³ of 0.5 N sodium hydroxide to keep the solution sufficiently alkaline. After cooling and drying, the yield is 162 g. of methyl-para-toluene - 1 - sulfonylamino - 2 - nitro-4-(N,N,methyl-carbamylmethyl)amino benzene which, after recrystallization in acetic acid, melts at 184° C.

Analysis.—Calcd. for $C_{17}H_{20}N_4O_5S$ (percent): C, 52.04; H, 5.10; N, 14.29. Found (percent): C, 52.02–52.17; H, 5.25–5.20; N, 14.41–14.39.

(c) Preparation of 1 - methylamino-2-nitro-4-(N,N, methyl - carbamylmethyl)amino benzene.—0.294 mols (115 g.) of methyl-para-toluene-1-sulfonylamino-2-nitro-4-(N,N-methyl carbamylmethyl)amino benzene is added little by little, while stirring vigorously, to 230 cm.³ of concentrated sulfuric acid, while maintaining the temperature between 0° and 5° C. After leaving the reaction mixture for four hours at this same temperature, it is poured over two kg. of cracked ice. After neutralization with ammonia, drying yields 68 g. of 1-methylamino-2-nitro - 4-(N,N-methyl carbamylmethyl)amino benzene, which melts at 184° C.

Analysis.—Calcd. for $C_{10}H_{14}N_4O_3$ (percent): C, 50.41; H, 5.88; N, 23.53. Found (percent): C, 50.62–50.45; H, 6.20–6.16; N, 23.75–23.54.

(d) Preparation of the monohydrochloride of 1-methylamino - 2 - nitro-4-(N,N,methyl carboxymethyl) amino benzene.—0.286 mols (68 g.) of 1-methylamino-2-nitro-4-(N,N-methyl carbamylmethyl)amino benzene is dissolved in 250 cm.³ of concentrated hydrochloric acid. This is brought to reflux for 45 minutes. After cooling, drying yields 72.5 g. of the monohydrochloride of 1-methylamino - 2 - nitro-4-(N,N-methyl carboxymethyl) amino benzene, which melts and decomposes at 150° C.

Analysis.—Calcd. for $C_{10}H_{14}N_3O_4Cl$ (percent): C, 43.55; H, 5.08; N, 15.24. Found (percent): C, 43.53–43.24; H, 5.11–5.18; N, 15.38–15.41.

EXAMPLE 3

Preparation of the monohydrochloride of 1-(β-hydroxyethylamino) - 2-nitro-4-(N,N,methyl carboxymethyl) amino benzene

The above compound has been prepared by a new method essentially characterized by the fact that chloroacetamide is caused to act on the secondary amine function in the meta position relative to the nitro group of 1-amino-2-nitro-4-methylamino benzene and β-chloroethyl chloroformate is reacted with the resulting 1-amino-2-nitro-4-(N,N,methyl carbamylmethyl)amino benzene to obtain the β-chloroethyl ester of [2-nitro-4-(N,N-

methyl carbamylmethyl)amino] phenyl carbamic acid. The amide function of this ester is hydrolyzed with hydrochloric acid and the resulting compound is subjected to an alkaline hydrolysis followed by acidification with hydrochloric acid. The above process is illustrated by the following diagram:

(a) Preparation of 1-amino-2-nitro-4-(N,N-methyl carbamylmethyl)amino benzene.—A mixture of 0.4 mols (66.8 g.) of 1-amino-2-nitro-4-methylamino benzene, 800 cm.³ of water and 80 g. of calcium carbonate is brought to reflux. 1.2 mols (112.5 g.) of chloroacetamide is added little by little, while stirring. Reflux is continued for an hour after this addition has been completed. The mixture is then cooled and acidified to pH 3 with hydrochloric acid. Drying yields 86 g. of 1-amino-2-nitro-4-(N,N-methyl carbamylmethyl)amino benzene, which after recrystallization in acetic acid, melts at 238° C.

Analysis.—Calcd. for C₉H₁₂O₃N₄ (percent): C, 48.21; H, 5.35; N, 25.00. Found (percent): C, 48.58–48.29; H, 5.45–5.50; N, 24.86–24.90.

(b) Preparation of the β -chloroethane ester of [2-nitro-4-(N,N-methyl carbamylmethyl)amino]-phenylcarbamic acid.—1.45 mols (325 g.) of 1-amino-2-nitro-4-(N,N-methyl carbamylmethyl)amino benzene is dissolved in two liters of dioxane. After adding 105 g. of calcium carbonate, 1.7 mols (244 g.) of chloroethylchloroformate is introduced little by little, at reflux and while stirring. Reflux is continued for three hours. The mixture is filtered while boiling to eliminate the mineral salts and the filtrate is refrigerated overnight. Drying yields 320 g. of the β -chloroethylic ester of [2-nitro-4-(N,N-methyl carbamylmethyl)amino]-phenylcarbamic acid, which, after recrystallization in alcohol, melts at 145° C.

Analysis.—Calcd. for C₁₂H₁₅O₅N₄Cl (percent): C, 43.57; H, 4.54; N, 16.94. Found (percent): C, 44.48–44.25; H, 4.52–4.67; N, 17.31–17.34.

(c) Preparation of the β -chloroethylic ester of [2-nitro-4-(N,N-methyl carbamylmethyl)amino]-phenylcarbamic acid.—0.1 mols of the β -chloroethylic ester of [2-nitro-4-(N,N-methyl carbamylmethyl)amino]-phenylcarbamic acid is introduced, while stirring, into 450 cm.³ of 5 N hydrochloric acid, while boiling to reflux. When the product is entirely dissolved, reflux is continued for another 15 minutes and the reaction mixture is then poured into 500 cm.³ of ice water. Drying yields 19 g. of the β -chloroethylic ester of [2-nitro-4-(N,N-methyl carbamylmethyl)amino]-phenylcarbamic acid, which, after recrystallization in a mixture of acetic acid and water, melts at 147° C.

Analysis.—Calcd. for C₁₂H₁₄O₆N₃Cl (percent): C, 43.43; H, 4.22; N, 12.67. Found (percent): C, 44.05–44.14; H, 4.34–4.25; N, 13.02–13.10.

(d) Preparation of the monohydrochloride of 1- β -hydroxyethylamino-2-nitro-4-(N,N-methyl carbamylmethyl)amino benzene.—0.034 mols (11.2 g.) of β -chloroethylic ester of [2-nitro-4-(N,N-methyl carbamylmethyl)amino]-phenylcarbamic acid is dissolved in 58.5 cm.³ of 3 N sodium hydroxide, and brought to reflux for an hour. It is then cooled and acidified with 17 cm.³ of concentrated hydrochloric acid. Drying yields 6.5 g. of the mono-hydrochloride of 1- β -hydroxyethylamino-2-nitro-4-(N,N-methyl carbamylmethyl)amino benzene, which, after recrystallization in 2 N hydrochloric acid, melts and decomposes at 135° C.

Analysis.—Calcd. for C₁₁H₁₆N₃O₅Cl (percent): C, 43.20; H, 5.24; N, 13.75; Cl, 11.62. Found (percent): C, 43.48–43.37; H, 5.39–5.35; N, 13.58–13.64; Cl, 11.61–11.78.

EXAMPLE 4

Preparation of the monohydrochloride of 1-methylamino-2-nitro- β -carboxymethylamino benzene

The above compound has been prepared by a new method essentially characterized by the fact that β -chloropropionamide is condensed on 1-methylamino-2-nitro-4-amino benzene and that the amino function of the resulting product is hydrolyzed with hydrochloric acid to yield the monohydrochloride of 1-methylamino-2-nitro-4- β -carboxymethylamino benzene.

The above process is schematically illustrated by the following diagram:

(a) Preparation of 1-methylamino-2-nitro-4- β -carboxymethylamino benzene.—A mixture of 0.4 mols (64 g.) of 1-methylamino-2-nitro-4-amino benzene with 900 cm.³ of water and 21 g. of calcium carbonate is heated to reflux. 0.4 mols (43 g.) of β -chloropropionamide is introduced, little by little, while stirring.

Reflux is continued for two hours. The mixture is filtered while boiling and, after drying and cooling the filtrate, yields 65 g. of the crude product. This, after washing with boiling toluene to eliminate the 1-methylamino-2-nitro-4-amino benzene which has not re-

acted, and after recrystallization in dioxane, melts at 157° C.

Analysis of end product.—Calcd. for $C_{10}H_{14}O_3N_4$ (percent): C, 50.41; H, 5.88; N, 23.52. Found (percent): C, 50.24–50.48; H, 5.99–5.82; N, 23.45–23.41.

(b) Preparation of monohydrochloride of 1-methylamino-2-nitro-4- β -carboxyethylamino benzene.—0.021 mol (5 g.) of 1-methylamino-2-nitro-4- β -carbamylethylamino benzene is introduced, while stirring, into 25 cm.³ of concentrated hydrochloric acid diluted with 13 cm.³ of water. This is brought to reflux, where it is maintained for half an hour. When cooled and dried, the yield is 4.5 g. of the monohydrochloride of 1-methylamino-2-nitro-4- β -carboxyethylamino benzene which, after recrystallization in dilute hydrochloric acid, melts and decomposes at 170° C.

Analysis of end product.—Calcd. for $C_{10}H_{14}O_4N_3Cl$ (percent): C, 43.55; H, 5.08; N, 15.24. Found (percent): C, 43.58–43.64; H, 5.09–5.08; N, 15.53–15.48.

EXAMPLE 5

The following composition is prepared:

1 - methylamino - 2 - nitro-4-(N-methyl-N-carboxy- methyl)-amino benzene hydrochloride -----	0.3	G.
Lauric alcohol oxyethylenated with 10 molecules of ethylene oxide -----	25	
Sodium carbonate, q.s.p., pH=3	5	
Water, q.s.p. -----	100	

This composition is applied to golden yellow bleached hair, and is left in contact therewith for 20 minutes. The hair is then shampooed and rinsed. A pearly ash blond shade is obtained.

EXAMPLE 6

The following composition is prepared:

1 - methylamino - 2 - nitro-4-(N-methyl-N-carboxy- methyl)-amino benzene hydrochloride -----	0.6	G.
20% ammonium lauryl sulfate -----	5	
Sodium carbonate, q.s.p., pH=5	40	
Water, q.s.p. -----	100	

This composition is applied to light chestnut hair and left in contact therewith for 40 minutes. The hair is then shampooed, rinsed and dried. The result is a chestnut shade with reddish gold glints.

EXAMPLE 7

The following composition is prepared:

1-(β -hydroxyethyl)-amino - 2 - nitro-4-(N-methyl-N- carboxymethyl)-amino benzene hydrochloride -----	0.6	G.
1-hydroxy-2-amino-5-nitrobenzene -----	0.01	
Lauric alcohol oxyethylenated with 12 molecules of ethylene oxide -----	5	
Sodium carbonate, q.s.p., pH=9	55	
Water, q.s.p. -----	100	

This composition is applied to chestnut hair, 50% of which has turned white, and left in contact therewith for 20 minutes. The hair is then shampooed and rinsed. The result is a maroon violet chestnut.

EXAMPLE 8

The following composition is prepared:

1-(β -hydroxyethyl)-2-amino - 4 - nitro-(N-methyl-N- carboxymethyl)-amino benzene hydrochloride -----	0.5	G.
20% lauryl ammonium sulfate -----	5	
Sodium carbonate, q.s.p., pH=8	65	
Water, q.s.p. -----	100	

This composition is applied to naturally light chestnut hair, and left in contact therewith for 35 minutes. The hair is then shampooed and rinsed. A light burnt chestnut shade results.

EXAMPLE 9

The following composition is prepared:

1 - methylamino-2-nitro-4-(N-carboxymethyl)-amino benzene hydrochloride -----	0.8	G.
Sodium carbonate, q.s.p., pH=9.5	5	
20% lauryl ammonium sulfate -----	100	
Water, q.s.p. -----	100	

This composition is applied to deep blond hair and left in contact therewith for 30 minutes. The hair is then shampooed and rinsed. A light violine chestnut shade results.

EXAMPLE 10

The following composition is prepared:

Lauryl alcohol oxyethylenated with 10 molecules of ethylene oxide -----	5	G.
1 - methylamino-2-nitro-4-(N-carboxymethyl)-amino benzene hydrochloride -----	0.8	
Sodium carbonate, q.s.p., pH=3	100	
Water, q.s.p. -----	100	

This composition is applied to blond hair, and left in contact therewith for 40 minutes. The hair is then shampooed and rinsed. A deep pearly blond shade results.

EXAMPLE 11

The following composition is prepared:

1 - methylamino - 2 - nitro-4-(N-methyl-N-carboxy- methyl)-amino benzene hydrochloride -----	0.14	G.
4-nitro-1,3-phenylenediamine -----	0.02	
20% ammonia, q.s.p., pH=3	100	
Water, q.s.p. -----	100	

This composition is applied to bleached straw-colored hair, and left in contact therewith for 15 minutes. The hair is then rinsed, shampooed, and rinsed again. After drying, the result is a beige with glints of burnt pearl.

EXAMPLE 12

The following composition is prepared:

1-(β -hydroxyethyl)-2-amino - 4 - nitro-(N-methyl-N- carboxymethyl)-amino benzene hydrochloride -----	0.15	G.
4-nitro-1,3-phenylenediamine -----	0.02	
20% ammonia, q.s.p., pH=3	100	
Water, q.s.p. -----	100	

This composition is applied to bleached platinum blond hair, and left in contact therewith for 15 minutes. The hair is then rinsed, shampooed, rinsed again, and dried. A warm golden beige shade results.

EXAMPLE 13

The following composition is prepared:

1-(β -hydroxyethyl)-2-amino-4-nitro-(N-methyl, N- carboxymethyl)-amino benzene hydrochloride -----	0.24	G.
4-nitro-1,3-phenylenediamine -----	0.08	
20% ammonia, q.s.p., pH=3	100	
Water, q.s.p. -----	100	

This mixture is applied to 100% white hair, and left in contact therewith for 25 minutes. The hair is then rinsed, shampooed, rinsed again, and dried. A violet burnt blond shade results.

EXAMPLE 14

The following composition is prepared:

4-nitro-1,3-phenylenediamine -----	0.004	G.
1-methylamino-2-nitro-4-(carboxymethyl)-amino benzene hydrochloride -----	0.1	
Violet acetoquinone, Brilliant N -----	0.03	
Yellow acetoquinone, Brilliant RZ -----	0.03	
20% ammonia, q.s.p., pH=3	100	
Water, q.s.p. -----	100	

This composition, applied to 100% white hair, for 20 minutes, produces after rinsing, shampooing and drying, a very light blond with a slightly pearlescent glint.

EXAMPLE 15

The following composition is prepared:

1-methylamino-2-nitro-4- β -carboxyethylamino	G.
benzene hydrochloride	1
Sodium carbonate, q.s.q., pH=9	5
20% lauryl ammonium sulfate	10
Water, q.s.p.	100

This composition is applied to blond hair and left in contact therewith for 15 minutes. The hair is then shampooed and rinsed. A rose beige shade results.

It will be appreciated that the foregoing methods of carrying out the invention have been given purely by way of example and may be modified as to detail without thereby departing from the basic principles of the invention.

What is claimed is:

1. A compound having the formula:

in which n is 1 to 4.

2. A compound having the formula:

in which n is 1 to 4.

3. A compound having the formula:

in which n is 1 to 4.

4. The method of preparing 1-methylamino-2-nitro-4-(N,N-methyl carboxymethyl)amino benzene which comprises the steps of blocking the primary amine function of each mol of 1-amino-2-nitro-4-N,N-methyl carbamylamino benzene with about 1.1 mols of para-toluene sulfochloride at a temperature of about 45° C., reacting the reaction product with about 2.25 mols of methylsulfate per mol of reaction product at about 35-40° C. thereby substituting a methyl radical for the free hydrogen remaining on said primary amine function, eliminating the SO₂ radical used for blocking purposes, and hydrolyzing the amide function of the resulting composition.

5. The method claimed in claim 4 in which said primary amine function is blocked by reaction with para-toluene sulfochloride and the SO₂ radical is eliminated by treating each mol of the resulting product with about 15 mols of concentrated sulfuric acid, at a temperature of about 0 to 5° C.

6. The method of preparing the monohydrochloride of 1-(β -hydroxy-ethylamino)-2-nitro-4-(N,N-methyl-carboxymethyl)amino benzene which comprises the steps of reacting about 3 mols of chloroacetamide with each mol of the secondary amine function in the methylamine group of 1-amino-2-nitro-4-methylamino benzene under reflux conditions, reacting about 1.2 mols of β -chloroethyl chloroformate with each mol of the resulting product under reflux conditions to obtain the β -chloroethyl ester of [2-nitro-4-(N,N-methyl carbamylmethyl)amino] phenylcarbamic acid, hydrolyzing the amide function of said ester, hydrolyzing the resulting product in an alkaline solution, and then acidify the resulting product.

7. The method of claim 6 in which about 22.5 mols of hydrochloric acid are used to hydrolyze each mol of the amide function of said ester and 5 mols of sodium hydroxide is used per mol of reaction product to hydrolyze said reaction product under reflux conditions.
